UNITED STATES PATENT OFFICE

157,432

GARDEN TRACTOR

Herbert C. Roths, Alma, Mich., assignor to Roths
Industries, Inc., Alma, Mich.

Application December 19, 1946, Serial No. 135,606

Term of patent 14 years

(Cl. D35—1)

To all whom it may concern:

Be it known that I, Herbert C. Roths, a citizen of the United States of America, residing at Alma, in the county of Gratiot and State of Michigan, have invented a new, original, and ornamental Design for Garden Tractors, of which the following is a specification, reference being had to the accompanying drawings, forming part thereof.

In the drawings:

Fig. 1 is a side elevational view of a garden tractor, showing my new design.

Fig. 2 is a top, plan view thereof.

Fig. 3 is a rear elevational view; and

Fig. 4 is a front elevational view.

Fig. 5 is a sectional, side elevational view of the tractor taken on the line 5—5 of Fig. 2.

I claim:

The ornamental design for a garden tractor, as shown.

HERBERT C. ROTHS.
